DESIGN FOR A RADIO SPEAKER WALL CABINET

Michel de Heurtaumont and Harvey J. Sines,
Beverly Hills, Calif.

Application August 28, 1936, Serial No. 64,609

Term of patent 3½ years

To all whom it may concern:

Be it known that we, Michel de Heurtaumont, a citizen of the Republic of France, and Harvey J. Sines, a citizen of the United States of America, both residing in the county of Los Angeles, State of California, have invented a new, original, and ornamental Design for a Radio Speaker Wall Cabinet, of which the following is a specification, reference being had to the drawing, forming a part thereof.

The drawing is a front perspective view of our new design and the radio speaker wall cabinet

illustrated therein is adapted to be mounted in a wall or like structure so that only the outer face of the grill is visible when the same is installed for use. The rearwardly extending portion of the cabinet is substantially rectangular in shape.

We claim:

The ornamental design for a radio speaker wall cabinet as shown and described.

MICHEL DE HEURTAUMONT.
HARVEY J. SINES.
